MACHINE FOR TREATING FURS

Samuel Deutscher, Brooklyn, N. Y.

Application November 5, 1940, Serial No. 364,374

10 Claims. (Cl. 149—24)

My invention relates to fur treating machines and has particular reference to machines for preliminary treatment of furs prior to sewing them into garments.

One of the first steps in fur treatment consists in wetting the leather side of the furs, this operation being usually performed by hand, using wet sponges. The manual process is very slow, however, having also another disadvantage in that water from the sponges gets on the hair side of the furs, rendering further operations with the fur more difficult, especially for matching skins.

My invention has for its object to provide a machine in which pieces of fur or pelts can be automatically wetted on the leather side; then, after turning the pelts over, they can be automatically combed and brushed. My machine can be also provided with a separate attachment for rubbing and stretching the pelts after they have been wetted.

My invention is more fully described in the accompanying specification and drawings, in which:

Fig. 1 is a sectional elevational view of my machine showing a piece of fur placed in position to have its leather side wetted;

Fig. 2 is a similar sectional view showing a piece of fur placed in position for combing its hair, the wetting brush being covered by a shield;

Fig. 3 is a top plan view partly in section;

Fig. 4 is an end view partly in section;

Fig. 5 is a detail view of combs;

Fig. 6 is an end view of a fur rubbing attachment;

Fig. 7 is a fractional top plan view of the same; and

Figs. 8, 9, and 10 are detail views of the modified ports and sleeves.

My fur treating machine consists of a base 1 preferably of a rectangular shape with four posts 2 at the corners. The posts support bars 3 (Figs. 3 and 4) at the front and at the rear to which are fastened as by welding the ends of relatively thin bars 4 extending from the front to the rear and having sharp teeth 5 at the top. Thin wires 6 are also stretched between the bars 4 suitably attached to the bars 3 at the level of the teeth 5, the bars and wires forming a grid for supporting a piece of fur or pelt 7. If desired, additional thin wires may be provided extending transversely of the longitudinal wires 6. The fur is pressed against the wires and bars by a heavy plate 8 slidably fitted on the posts 2 and suspended on cables or wires 9 passing over pulleys 10. The other ends of the wires are wound on pulleys 11 rotatively mounted on a shaft 12, rotated by a motor 13. Magnetic clutches 14 are provided for connecting the pulleys 11 with the shaft. Handles 14' are also provided for manual opera-

tion of the cables. An identical arrangement is provided at the other end of the machine.

The leather side of the fur is wetted by a rotary brush 15 consisting of sections 15, 15', etc., mounted on a common shaft 16. The sections are separated by distances corresponding to the thickness of the bars 4. The shaft 16 is journaled in the end walls of a tank 17 open at the top and adapted to hold water 17' or other liquid used for wetting the fur. The brush is rotated by a motor 19 mounted on the extension of the bottom of the tank, the rotation being transmitted by a belt or chain 20 and pulleys 21 and 22. The motor is also connected by a belt or chain 23 with a pulley 24 on one of the wheels 25 of the tank. The wheels are placed on guiding rails 26 extending longitudinally of the machine.

The effective area covered by the supporting bars 4 and wires 6 is sufficiently large for a number of pelts treated simultaneously. Since some of the pelts may require less wetting than the others, a regulating device is provided in the form of wiper bars 27, which may be of metal, rubber or other suitable material.

They are mounted on legs 28 pivoted on a shaft 29 and have handles 30 extending outside the tank. The wiper bars are retained in different positions by friction blocks 31 made of rubber or similar elastic material, engaging grooves 32 in the handles 30. By pushing the handles inward, the wiper bars come in contact with the bristles of the brushes, wiping off the excess of water. The wiping effect can be regulated by the degree of advance of the wiper bars against the brushes. Additional wipers 33 become effective when the handles 30 are moved sufficiently far inward.

The tank with the brushes is brought to the rear end of the machine before the fur is placed on the supporting grid. The motor 13 and magnetic clutches 14 are then energized, causing the plate 8 to descend and to press the fur against the grid. At the same time lugs 34 engage push buttons 35, closing circuit for the motor 19. The latter rotates the brushes and propels the tank to the front end of the machine, the brushes rubbing and wetting the leather side of the fur. At the end of the tank movement, the circuit for the motor 19 is interrupted, causing the brush and the tank to stop. At the same time the motor 13 is started in the opposite direction with the clutches 14 engaged, causing the plate 8 to be raised. The furs can be then removed from the grid.

For combining the hair, the fur is placed on the grid with the hair side down. The brushes are then covered by plates 36 mounted on legs 37 slidably supported between guiding rails 38 on a plate 39 forming extension of the tank bottom, the legs being joined at the bottom by a cross-

bar 40. The plates are shown in the opened position in Fig. 1 and in the closed position in Fig. 2. The plates have slots 41 for straight brushes 42 slidably supported on the wall 43 of the tank, so that they can be moved upward for brushing the hair side of the fur when the rotary brush is covered with the plates 36.

Handles 44 are provided on the brushes 42 for moving them into an operative position. They are also guided by pins 45 sliding in slots 46 in the shanks of the brushes.

At the front wall 47 of the tank there are provided combs 48 and 49 with their shanks 50 and 51 slidably supported between rails 52 at the ends of the tank. The comb 49 has handles 53 passing through slots 54 in the outer wall 55, and the comb 48 has a handle 55 passing through a slot 56 in the outer wall and also through a corresponding slot in the outer comb 49. The combs are protected in their lowered position by a shield 50' hinged at 51', so that it can be lowered and placed out of the way of the combs when the latter are raised, as shown in Fig. 2.

Due to the fact that pieces of fur cannot cover the entire surface of the pressure plate 8, the latter may be wetted in spots by the rotary brush during the wetting operation, and this moisture may be later transmitted to the hair of the next batch of furs. Means is therefore provided for drying the under side of the plate 8 when it is raised. This may be accomplished by blowing hot air over the surface of the plate through pipes 57 from a blower 58, the air passing through an electric heater 59, after the plate 8 has been raised above the level of the blower ducts.

A wiper roll 60 may be also provided as shown in Fig. 2, the ends of the roll being guided between rails 61 at the sides of the machine. The roll is pulled from one end of the machine to the other by cables or cords 62 passing over sheaves 63 and wound on pulleys 64 on the shaft 16 and provided with magnetic clutches after the plate 8 has been raised above the rails 61. The operation of the wiper roll as well as the blower may be made automatic, corresponding contacts being closed when the plate 8 is raised, the contacts being open again when the wiper completes one cycle of movement back and forth. It is understood that both devices, blower and wiper, can be used at the same time.

It should be noted that while the wires 6 and bars 4 can be spaced at short distances apart, so that they will support short pieces and corners of the fur, additional supporting wires 66 may be provided mounted transversely of the wires 6 on the ends of yokes formed of vertical rods 67 joined at the top with bars 68. The rods slide with certain friction in corresponding holes in a rectangular frame 69 mounted on the posts 2 and supported by bushings 70. The yokes formed by the rods and bars 68 can be therefore raised or lowered individually and will remain in any such position. The yokes are raised by a frame 71 sliding over the posts 2 and suspended on cords or cables 73 passing over pulleys 72 and wound on pulleys 74 on the shaft 16, the connection between the latter and the pulleys 74 being effected by magnetic clutches. The yokes are lowered by the pressure from an upper frame 76 sliding on the posts 2 and suspended on cords or cables 77 passing over pulleys 78 and wound on pulleys 79 on the shaft 16, the pulleys 79 having magnetic clutches 80. Buffer springs 81 are provided on top of the rods 67 in order to equalize the pressure on the wires 66 when the latter are placed on the

bars 4 if there is a slight difference in length between the rods 67.

The wires 66 are used for supporting a piece of fur during the process of wetting its leather side, as shown in Fig. 1. The wires 66 and yokes 5 may be omitted, however, if the stationary wires 6 are closely spaced and even reinforced by cross wires (not shown).

My machine can also be used for rubbing and stretching the fur, so as to remove folds and wrinkles. Levers 82 (Fig. 1) are provided for this purpose pivoted at 83 to the posts 37 and having a rounded bar 84 extending between the adjacent bars 4. The bar 84 is pressed against the leather side of the fur, while the other leg of the lever slides over corrugations 85 on the base 1.

The bar rubs or irons the fur with jerking movements, similar to the movement when the fur is rubbed by hand. Sheet metal protectors 86 are clamped on the teeth 5 between the bars 84, so as to allow stretching of the fur on the bars 4. A spring 87 keeps the lever pressed against the corrugations 85.

The rubbing of the fur 7 can be also made on an attachment to my machine shown in Figs. 6 and 7. The base 1' may be an extension of the base 1 and the motor 13' may be the same motor 13, which operates the other part of the machine. A vertical board 88 is provided for supporting a piece of fur 7, which is clamped at the top with a heavy bar 89 having a rubber strip 90 and suitably guided at the ends. The fur is rubbed by hollow bars 91 supported on levers 92 pivoted at 93 on brackets 94 extending from sleeve 95 sliding on four posts 96. The outer lugs 97 of the levers slide over corrugations 98 on the posts. Pressure of springs 99 urging the brackets 94 and the bars is regulated by adjusting screws 100. The sleeves 95 are joined by bars 101 and are attached to cords or chains 102 passing over pulleys 103 and 104 on shafts 105 journaled in brackets 106 and 107 on the posts 96. The shafts are rotated by the motor 13' through gears 108 and 109, the shafts 105 being connected by a cord 102' on pulleys 110.

The motor may be provided with separate speed control for raising and lowering the sleeves. Hot air is admitted into the bars 91 through flexible tubes 111 from the blower 59, Fig. 1, the air emerging through small holes 112. Additional cloth rolls 113 may be provided for wiping the board 88 when the fur is removed, the rolls having fabric flaps attached to the sides of the bars 91.

The operation of the motor is preferably so arranged that the bars 91 move downward when the fur is clamped by the bar 89 and close corresponding contacts, the motor being automatically stopped by another set of contacts when the bars complete their downward travel.

The motor is reversed by a hand switch for moving the bars upward, a hot air blast being at the same time started for drying the board 88.

Several parallel boards 88 may be provided for simultaneous treatment of a number of pelts. The sleeves 95 may be provided with levers 92 at both sides, the brackets 106 and 107 being then mounted on the end sides of the posts 96.

The device can be also used for ironing seams in a piece of fur prepared for making a coat. To make the seams smooth, they must be rubbed with a steady motion of the ironing bars 91. A modified arrangement for this purpose is shown in Fig. 8. The posts 113' are smooth and have bars 114 placed at their sides and attached by

screws 115, passing through holes in sleeves 95'. The bars 114 have teeth 98, the lugs 97 being sufficiently wide partly to cover both the posts and bars 114. Holes 116 for the screws are made wide in horizontal direction, so that the bars 114 can be clamped either in the operative position with the teeth extending above the post 113' as shown in Fig. 8, or they can be withdrawn, in which case the lugs 97 will slide over the smooth surface of the posts 113'.

My machine can be used simultaneously for different operations in different sections, as, for instance, one section can be used for wetting furs, another for combing and wetting at the same time, the third for combing only, the fourth for moderate wetting, using wiper bars 21.

It is understood that my fur treating machine may be further modified without departing from the spirit of the invention, as set forth in the appended claims.

I claim as my invention:

1. A fur wetting and combing machine comprising a base, means to support a piece of fur at an elevation above the base, an open tank movably supported on the base, a brush rotatively supported in the tank and adapted to press against the fur, the tank being adapted to contain a liquid for moistening the brush, means on the tank to rotate the brush, means to move the tank with the brush under the fur supporting means, means on the base to guide the tank, and a plurality of wipers adjustably supported at the brush for wiping the brush.

2. A fur wetting and combing machine comprising a base, means to support a piece of fur at an elevation above the base, an open tank movably supported on the base, a brush rotatively supported in the tank and adapted to press against the fur, the tank being adapted to contain a liquid for moistening the brush, means on the tank to rotate the brush, means to move the tank with the brush under the fur supporting means, means on the base to guide the tank, a plurality of combs movably supported at the sides of the tank adapted to be raised for engaging the fur, and means to render the brush inoperative when the combs are raised.

3. A fur wetting and combing machine comprising a base, means to support a piece of fur at an elevation above the base, an open tank movably supported on the base, a brush rotatively supported in the tank and adapted to press against the fur, the tank being adapted to contain a liquid for moistening the brush, means on the tank to rotate the brush, means to move the tank with the brush under the fur supporting means, means on the base to guide the tank, a plurality of combs movably supported at the sides of the tank adapted to be raised for engaging the fur, and a cover plate slidably supported on the tank adapted to be moved over the brush when the combs are raised.

4. A fur wetting and combing machine comprising a base, means to support a piece of fur at an elevation above the base, an open tank movably supported on the base, a brush rotatively supported in the tank and adapted to press against the fur, the tank being adapted to contain a liquid for moistening the brush, means on the tank to rotate the brush, means to move the tank with the brush under the fur supporting means, means on the base to guide the tank, a plurality of combs movably supported at the sides of the tank adapted to be raised for engaging the fur, means to render the brush inoperative

when the combs are raised, and a hinged cover on the tank for covering the combs in their lowered position.

5. A fur treating machine comprising a base, a plurality of elongated members supported at an elevation above the base adapted to support a piece of fur, a plate movably supported above the elongated members adapted to be placed on the fur for pressing it against the elongated members, a tank movably supported on the base under the elongated members, fur treating members movably and adjustably supported at the tank, and means to move the tank in a direction parallel to the elongated members.

15 6. A fur treating machine comprising a base, a plurality of elongated members supported at an elevation above the base adapted to support a piece of fur, a plate movably supported above the elongated members adapted to be placed on the fur for pressing it against the elongated members, a tank movably supported on the base under the elongated members, fur treating members movably and adjustably supported at the tank, means to move the tank in a direction parallel to the elongated members, and means to control the movements of the tank by the movement of the plate.

20 7. A fur treating machine comprising a base, a plurality of elongated members supported at an elevation above the base adapted to support a piece of fur, a plate movably supported above the elongated members adapted to be placed on the fur for pressing it against the elongated members, a plurality of yokes movably supported above the plate, wires stretched between the lower ends of the yokes adapted to rest on the elongated members under the fur when the yokes are lowered, and fur treating members movably supported under the base under the elongated members.

25 8. A fur treating machine comprising a base, a plurality of bars supported at an elevation above the base, the upper edges of the bars having sharp teeth, a plurality of yokes movably supported above the bars in planes perpendicular to the plane of the bars, wires stretched between the lower ends of the yokes adapted to be placed in spaces between the teeth on the bars, the wires and the bars being adapted to support a piece of fur, means on the base under the bars to treat the fur, and a plate movably supported above the bars adapted to press the fur against the bars.

30 9. A fur treating machine comprising a base, a plurality of bars supported at an elevation above the base, the upper edges of the bars having sharp teeth, posts on the base, yokes movably supported on the posts above the bars, wires stretched between the lower ends of the yokes adapted to be placed on the bars between the teeth for supporting a piece of fur, a plate movably supported on the posts adapted to be lowered for pressing the fur against the wires and bars, and means to move the yokes for raising and lowering the wires.

35 10. A fur treating machine comprising a base, means to support a piece of fur at an elevation above the base, means to clamp the fur against the supporting means, members adapted to engage the fur for its treatment, means to movably support the members on the base, an electric motor on the base, means to move the member supporting means by the motor, and cam members on the base to cause the members to vibrate in their movement and to press the fur treating members against the fur.

SAMUEL DEUTSCHER.
